ATTORNEY

UNITED STATES PATENT OFFICE.

MITTIE TAYLOR BRUSH, OF DUBLIN, NEW HAMPSHIRE.

REINFORCED TRANSPARENT SHEET AND PROCESS OF MAKING THE SAME.

Application filed February 26, 1927. Serial No. 171,330.

The present invention relates to a transparent composite sheet designed particularly for use for the curtain lights of motor vehicles and other windows but useful generally as a 5 transparent surfacing material; and the object thereof is to provide a reenforced composite sheet which not only is transparent, or substantially transparent, but will not tear and is both tough and flexible so that it will 10 not be broken, or at least will not be shattered, by blows or impact.

My new composite sheet consists, broadly stated, of a body of some suitable cellulose derivative, such for example as celluloid, pyraline, or one of the usual cellulose acetates, 15 and, incorporated therein, a meshwork of wires or of fibre threads either simply crossed or netted together.

In practice, I prefer for the body of the 20 sheet a liquid solution of cellulose acetate, which, when spread and dried, forms a tough flexible sheet that is quite clear and transparent and at the same time burns slowly so as to be practically non-combustible, and for 25 the reenforcement, particularly for curtain lights and similar uses, a meshwork of fine tinned spring music wires, of No. .004 to .008 gauge for example, spaced apart and crossed to provide a mesh of from one to two inches.

The great difficulty encountered in the manufacture of the sheets has been in satisfactorily incorporating therein the fine reenforcing wires or threads, which curl or bend and get out of place. I have obviated this difficulty by weaving the meshwork of reenforcing wires or threads in a loom within a border or frame of linen or cotton threads, which border is then sized in a thin solution preferably of a gelatine size such for example as 30 French size and stretched and dried, and, when dry, will hold the reenforcing elements taut. The solution having been spread in a sheet of the desired thickness over a plate of glass or metal, the surface of which has been 35 slightly moistened with glycerine, the reenforcement framed and held as stated is laid thereon and sinks or is pressed down and so becomes embedded therein; or, if desired, the reenforcement can be compiled between two 40 previously formed sheets, of celluloid, pyraline, or similar composition, which can then be united in the usual or in any suitable manner by the application of heat and pressure.

Another way of holding the reenforcement 45 in place is to string the wires around, or

stretch a reticular fabric of linen or other threads upon, a frame of thin steel and, after the reenforcement has been incorporated in the sheet, to cut the sheet out of the frame, which can be used repeatedly. 50

For certain uses the reenforcing wires or threads may be arranged more closely together so as to form say a one-quarter inch mesh, a netting of threads having wires inserted therein at intervals if desired, in which case the reenforcement may first be suitably secured in place and then the solution can be applied thereto so as to cover and envelope the reenforcing elements and fill in the openings. And where wires are used for the reenforcement and they are of a size or character 55 to hold themselves in place the border or frame may be omitted, the wire mesh being simply unrolled over and allowed to sink into the liquid sheet of celestrone. 75

Practical embodiments of the invention are shown, by way of illustration and not of limitation, in the accompanying drawings, in which—

Figure 1 is a side or plan view of a composite sheet, partially broken away, having incorporated therein a reenforcement of fine wires framed within a textile border; Fig. 2 is an enlarged sectional detail of a portion of such sheet; Fig. 3 is a plan or side view of a portion of another sheet, illustrating a modification; Fig. 4 is a sectional detail thereof similar to Fig. 2; and Fig. 5 is a plan or side view of a third sheet, illustrating a further modification. 80 85 90

As shown in Figs. 1 and 2, *a* indicates the body of the sheet and *b* the wires and *c* the woven textile border of the reenforcement which is incorporated therein. The sheet here illustrated is provided, midway its 95 length, with an intermediate border *c* of woven textile fabric, of double the width of the outer border, thus forming a double sheet which can be cut along the center of the intermediate border into two separate sheets. The border, or at least all but its inner edge, need not be incorporated in the body of the sheet, thus providing, when the sizing is removed therefrom, a soft flexible border by which the sheet can be sewed in 100 place. 105

In the modification illustrated in Figs. 3 and 4, *a* indicates the composition body of the sheet and *b* a netting of linen or other suitable fibre threads embedded therein. 110

This netting is stretched upon a thin metal frame c^1 , by passing its outer loops over the projections formed between notches in the outer edge of the frame. A meshwork of 5 fine crossed wires can be strung on the frame in a similar manner. Here only the reenforcing elements within the frame are incorporated in the composition sheet, the frame forming no part of the finished sheet which, 10 when hardened, is cut out from the frame.

In the further modification illustrated in Fig. 5, a^2 indicates the body of the sheet and b^2 the reenforcement of woven wire mesh. This sheet is formed, where the wires are 15 stiff enough to hold themselves in place, by simply unrolling the woven mesh over and allowing it to sink into a sheet of the cellulose acetate solution while in liquid or fluid condition.

20 The term "transparent" is used herein and in the claims as meaning "substantially transparent" or "translucent".

What I claim as new, and desire to secure by Letters Patent, is—

25 1. The process of making a sheet of the character described which comprises forming a meshwork of fine spring wires within a border of sized woven fibre threads and incorporating the wires so framed in a transparent sheet of a cellulose derivative.

30 2. The process of making a composite sheet of the character described which comprises

forming a meshwork of fine reinforcing elements within a border of sized woven fibre threads, spreading in a sheet a solution of a 35 cellulose derivative forming on hardening a tough and flexible transparent film, incorporating the reinforcing elements in said sheet while in fluid condition, and allowing the sheet to harden.

40 3. A reenforced transparent sheet comprising a body of a composition having for its base a cellulose derivative and incorporated therein a meshwork of fine reenforcing elements secured within a woven textile border. 45

4. A reenforced transparent sheet comprising a body of a composition having for its base a cellulose derivative and incorporated therein a meshwork of fine spring wires secured within a woven fabric border. 50

5. A reenforced transparent sheet comprising a body of a composition having for its base a cellulose derivative and incorporated therein both an open meshwork of fine spring wires and a woven textile border within 55 which the wire meshwork is secured.

6. The process of making a composite sheet of the character described which comprises forming a meshwork of fine reenforcing elements within a frame adapted to hold said elements tautly in position and incorporating the reenforcement while so framed in a sheet of a cellulose derivative. 60
